UNITED STATES PATENT OFFICE.

HERBERT C. BEASLEY, OF OAK PARK, AND ROBERT MACDOUGALL, OF DOWNTOWN GROVE, ILLINOIS, ASSIGNEES, BY MESNE ASSIGNMENTS, TO BEEMACK FURNACE COMPANY, A CORPORATION OF ILLINOIS.

FURNACE AND PROCESS OF OPERATING THE SAME.

Application filed July 14, 1924. Serial No. 725,774.

Our invention relates to improvements in furnaces and process of operating the same adapted particularly for treating and fusing enamel ware, although it is adapted to many other uses. It is applied to furnaces of the general type in which material to be treated is conveyed into the furnace and through it during the treating operation, and it has for one object to provide means whereby the conveyer which carries the material through the furnace, and particularly through the heated zone is cooled, and whereby escape of the heat from the furnace is prevented. Another object is to provide means whereby the material as it leaves the furnace is additionally cooled before actually leaving the furnace, and whereby material entering the furnace is heated by a blast of hot air. Other objects will appear from time to time throughout the specification and claims.

The furnace is of the general type in which two parallel lines of articles pass through the furnace in opposite directions on a continuous endless conveyer, and the ends of the furnace itself are thus open.

Our invention is illustrated more or less diagrammatically in the accompanying drawings, wherein:

Figures 1, 2 and 3 form together a diagrammatic plan view, Figures 1 and 3 showing opposite ends of the furnace, and Figure 2 the center section;

Figure 4 is a vertical cross section taken on line 4—4 of Figure 3;

Figure 5 is an enlarged view showing in detail the supporting members for the conveyer and the cooling means therefor;

Figure 6 is a detailed elevational view showing one end of the furnace;

Figure 7 is a vertical cross section on an enlarged scale taken on line 7—7 of Figure 6;

Figure 8 is a horizontal cross section on an enlarged scale taken on line 8—8 of Figure 6;

Figure 9 is a plan view in part section showing the conveyer chain;

Figure 10 is a detail generally in elevation and partly in section showing the conveyer chain.

Like parts are designated by like characters throughout.

A is the main burning or firing chamber of the furnace. It may be heated in any suitable manner. Preferably, however, it is heated electrically. In the preferred form the furnace is made generally of concrete with the addition of fire and heat resistant material, although it might be made of any suitable material. A¹ A¹ are supporting and strengthening beams which form part of the furnace structure. The burning chamber is preferably provided with a central partition A² which in effect divides it into two distinct chambers separated from each other.

The central burning chamber A opens directly at either end into two chambers B B. These chambers are provided with supporting and strengthening members B¹ B¹, and these burning chambers B are preferably not sub-divided within themselves. At the outer end of each of the chambers B is a pre-heating and pre-cooling chamber C which is provided with supporting members C¹.

D is an endless conveyer chain running through the furnace and extending at each end beyond it. At one end it runs by a supporting pulley or wheel D¹ which is carried and journaled in a frame-work D² and provided with longitudinal adjusting means D³ so that it may be moved in and out. At the other end the conveyer D is carried on a pulley D⁴ mounted on a shaft D⁵ which carries a bell wheel D⁶ driven by a pinion D⁷ mounted on a shaft D⁸. This shaft is driven by a reduction gear D⁹ from a pulley D¹⁰ which is itself driven from any suitable power source. By means of this construction the conveyer chain is moved through the furnace and carries the material in and out.

Running throughout the length of the furnace and extending through all of the chambers are two slots E. Above these slots the conveyer chain D is driven and through these slots material being moved through the furnace is supported from the conveyer. The conveyer chain includes suitable rollers E¹. These rollers run upon tracks E² E² above the slots E and above the furnace proper. The tracks are supported from the various beams B¹ B¹ and C¹. Forming a part of the chain and attached to it is a sectional moving inverted trough-like covering F for the slots E. This covering is made

up of a plurality of sections fastened to the chain links and adapted to fit each section with the other as shown particularly in Figure 9. This trough F penetrates into sand 5 F¹ held on either side of the slots E in troughs or depressions F².

Extending over the slots E throughout practically their entire length and covering them and the conveyer and tracks upon 10 which it runs and extending into the sand are hoods G.

In communication with the hoods G and preferably running lengthwise above the furnace is the main air conduit H. Air is 15 conveyed to this conduit through a pipe H¹ by means of a blower H². Between the blower H² and the conduit H is a valve structure H³ by means of which air may be allowed to escape before reaching the 20 conduit H so as to regulate pressure within the conduit system. At each end the conduit H communicates with the subsidiary conduits H⁴ which extend over the remaining part of the furnace and are in communication with the hoods G. Running from 25 the conduit H to the hoods G is a plurality of feeder pipes H⁵. By means of these pipes air which is forced into the conduit system is finally forced into the hoods G. 30 Toward the end of the main conduit H feeder pipes H⁶ which are smaller than the pipes H⁵ communicate with intermediate heating chambers B and bring air from the conduit to the hoods G above the intermediate chambers B. Communicating with the conduit H⁴ are feeder pipes H⁷ which communicate with the hood above the furnace chamber and take air to them at that point. 35

Adjacent the outer end of each of the 40 conduits H⁴ is a downwardly extending conduit I. This conduit communicates with a discharge box I¹ which is provided with a plurality of perforations I². This discharge box is situated at each end of the 45 furnace on the side of the furnace through which the outgoing material is carried, and the air coming from it blows upon the outwardly moving material. The air which is drawn into the conduit system is substantially uncooled, being usually room temperature although it might be cooled. 50

Although we have shown an operative device, still it will be obvious that many 55 changes might be made in size, shape and arrangement of parts without departing materially from the spirit of our invention; and we wish, therefore, that our showing be taken as in a sense diagrammatic.

The use and operation of our invention 60 are as follows:

The central chamber alone is heated to a suitable temperature. Some of the heat from this chamber, of course, penetrates into the intermediate chambers, and to a much 65 lesser degree even into the two outer cham-

bers. Raw material to be treated is put on the conveyer at each end of the furnace and thus there is moving into the furnace constantly in opposite directions two streams of material for treatment. As these streams 70 pass each other at either of the outer ends of the furnace, a stream of raw unheated material passes a stream of treated and partially cooled material.

Air is forced into the conduit system under comparatively small pressure. The pressure is sufficient to resist the pressure of the heated air which tends to leave the furnace through the slot in the roof, and thus 75 leakage of this heated air through the slots in the roof is practically prevented and the conveyer chain moving in the hood above this slot is comparatively cool and the difficulties of wear and lubrication are greatly 80 reduced. The amount of air forced into the hood above the various chambers is regulated by means of the size of the conduits and feeder pipes to conform to the varying degrees of pressure. The pressure of the 85 heated air in the central chamber is, of course, higher than that in the other 90 chambers.

At each of the outer ends of the furnace, the air in the conduit system which has not 95 been forced downward into the hoods covering the slots is finally forced into the discharge box. This is still substantially cool air and it is blown directly upon the outwardly moving stream of treated and partially cooled material and serves additionally to cool it. Since there is no partition in the outer chambers of the furnace, the partially cooled treated material moves directly past the cool untreated material and the heat from the partially cooled material 100 serves initially to heat the entering untreated material.

The blast of cool air which is blown upon the outwardly moving treated material 105 serves to cool it and is in this action itself heated and becomes thus a blast of heated air, and after becoming so heated moves directly across to the incoming stream of unheated, untreated material and thus serves 110 to heat it initially, at a point almost of its first entrance into the pre-heating chamber C of the furnace.

We claim:

1. In combination with an oven having a 115 slot in the roof thereof, a hood overlying said slot and means for preventing the escape of heated air through said slot, including said hood, and an air supply and conduit system adapted to force air under pressure 120 into said hood.

2. In combination with an oven having a 125 slot in the roof thereof, a hood overlying said slot and means for preventing the escape of heated air through said slot, including said hood, and an air supply and conduit 130

system adapted to force air under pressure into said hood, in combination with a conveyer adapted to run within said hood and above said slot.

5 3. In combination with an oven having a slot in the roof thereof, a hood overlying said slot and means for preventing the escape of heated air through said slot, including said hood, and an air supply and conduit system adapted to force air under pressure into said hood, in combination with a conveyer adapted to run within said hood and above said slot, said conveyer carrying an inverted hood adapted to overlie said slot

10 and to penetrate into a pair of sand filled troughs on either side of said slot.

4. In combination with an oven having a slot in the roof thereof, a hood overlying said slot and means for preventing the escape of heated air through said slot, including said hood, and an air supply and conduit system adapted to force air under pressure into said hood, in combination with an endless conveyer adapted to run within said hood and above said slot, said conveyer carrying an articulated inverted hood adapted to overlie said slot and to penetrate into a pair of sand filled troughs on either side of said slot.

25 5. In combination with an oven having a plurality of slots in the roof thereof, hoods covering said slots and means for preventing the escape of heated air through said slots, including said hoods, and an air supply and conduit system adapted to force air under pressure into said hoods.

30 6. In combination with an oven having a plurality of slots in the roof thereof, hoods covering said slots and means for preventing the escape of heated air through said slots, including said hoods, and an air supply and conduit system adapted to force air under pressure into said hoods, and an endless conveyer adapted to move within said hood and to support material within said ovens, said conveyer carrying an articulated inverted hood overlying said slots.

45 7. In combination with an oven having a plurality of slots in the roof thereof, hoods covering said slots and means for preventing the escape of heated air through said slots, including said hoods, and an air supply and conduit system adapted to force air under pressure into said hoods, and an endless conveyer adapted to move within said hood and to support material within said oven, said conveyer carrying an articulated inverted hood overlying said slots, and adapted to co-operate with pairs of sand filled troughs lying on either side of each of said slots to prevent the escape of heated air therethrough.

50 8. In combination with an oven having a pair of slots in its top, and an endless conveyer adapted to support material through

said slots and to move said material into and out of said oven in two oppositely moving streams, means for cooling one of said streams and for heating the other, including an air supply and conduit system adapted to blow a draft of cold air upon the stream of material leaving the oven and to blow said air after it leaves said heated material upon said entering cool material to heat the same.

9. In combination with an oven having a plurality of slots in the top thereof, and an endless conveyer adapted to move material into and out of said oven in two oppositely moving streams, a heating chamber within said oven adapted to heat said material, and cooling chambers on either side of said heating chamber, and means for preventing the escape of heated air from said slots, including hoods extending over said slots and an air supply and conduit system adapted to force air under pressure into said hoods.

10. In combination with an oven having a plurality of slots in the top thereof, and an endless conveyer adapted to move material into and out of said oven in two oppositely moving streams, a heating chamber within said oven adapted to heat said material, and cooling chambers on either side of said heating chamber, and means for preventing the escape of heated air from said slots, including hoods extending over said slots and an air supply and conduit system adapted to force air under pressure into said hoods, said endless conveyer carrying an articulated inverted hood-like trough overlying said slots.

11. In combination with an oven having a plurality of slots in the top thereof, and an endless conveyer adapted to move material into and out of said oven in two oppositely moving streams, a heating chamber within said oven adapted to heat said material, and cooling chambers on either side of said heating chamber, and means for preventing the escape of heated air from said slots, including hoods extending over said slots and an air supply and conduit system adapted to force air under pressure into said hoods, said endless conveyer carrying an articulated inverted hood-like trough overlying said slots, and co-operating with sand filled troughs on each side of each slot to prevent the escape of heated air therethrough.

12. In combination with an oven having a plurality of slots in the top thereof, and an endless conveyer adapted to move material into and out of said oven in two oppositely moving streams, a heating chamber within said oven adapted to heat said material, and cooling chambers on either side of said heating chamber, and means for preventing the escape of heated air from said slots, including hoods extending over said

- slots and an air supply and conduit system adapted to force air under pressure into said hoods, and means in combination with said conduit system for cooling the outgoing material and heating the ingoing material including a connection at each end of said conduit system and a discharge means adapted to blow air from the conduit system upon the heated outward stream of material and thus after such air has become heated upon the cool ingoing stream of material.
13. In combination with an oven having a plurality of slots in the top thereof, and an endless conveyer adapted to move material into and out of said oven in two oppositely moving streams, a heating chamber within said oven adapted to heat said material, and cooling chambers on either side of said heating chamber, and means for preventing the escape of heated air from said slots, including hoods extending over said slots and an air supply and conduit system adapted to force air under pressure into said hoods, said endless conveyer carrying an articulated inverted hook-like trough overlying said slots, and means in combination with said conduit system for cooling the outgoing material and heating the ingoing material, including a connection at each end of said conduit system and a discharge means adapted to blow cool air from the conduit system upon the heated outward stream of material and thence after such air has become heated, upon the cool ingoing stream of material.
14. In combination with an oven having a plurality of slots in the top thereof, and an endless conveyer adapted to move material into and out of said oven in two oppositely moving streams, a heating chamber within said oven adapted to heat said material, and cooling chambers on either side of said heating chamber, and means for preventing the escape of heated air from said slots, including hoods extending over said slots and an air supply and conduit system adapted to force air under pressure into said hoods, said endless conveyer carrying an articulated inverted hook-like trough overlying said slots, and co-operating with said filled troughs on each side of each slot to prevent the escape of heated air therethrough, and means in combination with said conduit system for cooling the outgoing material and heating the ingoing material, including a connection at each end of said conduit system and a discharge means adapted to blow cool air from the conduit system upon the heated outward stream of material and thence after such air has become heated, upon the cool ingoing stream of material.
15. The method of preventing the escape of heated air through an opening in an oven wall which consists in surrounding such opening with a zone of air under pressure substantially sufficient to overcome the pressure of the air within such oven.
16. In combination with an oven having an outside conveyor and an opening in said oven through which said conveyor extends, means for preventing the escape of heated air through such opening, including members adapted to surround said opening with a zone of pressure sufficient to prevent the escape of such heated air.
17. In combination with an oven having an outside conveyor and an opening in said oven through which said conveyor extends, means for preventing the escape of heated air through such opening, and means for maintaining along such opening an air pressure sufficient to prevent the escape of said heated air.
18. The method of preventing the escape of heated air through an opening in an oven wall which consists in surrounding such opening with a zone of air under pressure substantially equal to the pressure of the air within such oven.
19. A process for preventing the escape of air through an opening in an oven which consists in maintaining on the outer side of said opening a pressure only slightly in excess of that within the oven.
20. An oven having an opening through a wall thereof, means within the oven for moving materials to be treated therein, movable means outside the oven for operating the first said means, connections between the first and second said means extending through said opening, a hood over said openings and the second said means, and means for supplying said hood with gas under pressure.
